UNITED STATES PATENT OFFICE.

THOMAS GORMAN, OF WARREN, RHODE ISLAND, ASSIGNOR OF ONE-HALF
TO FRANK H. BROWN, OF WARWICK, RHODE ISLAND.

SPINDLE.

SPECIFICATION forming part of Letters Patent No. 663,492, dated December 11, 1900.

Application filed June 13, 1898. Serial No. 683,272. (No model.)

To all whom it may concern:

Be it known that I, THOMAS GORMAN, of Warren, in the county of Bristol and State of Rhode Island, have invented certain new and 5 useful Improvements in Spindles; and I do hereby declare the following specification, taken in connection with the accompanying drawings, forming a part of the same, to be a full, clear, and exact description thereof.

10 The invention relates to that class of spindles which have a sleeved whirl and are commonly used in ring-frame spinning-machines, and has for its object to provide a spindle which is simple in construction, which is not 15 liable to get out of order, which may be readily and cheaply repaired, and which may be run at a high rate of speed without chattering and without undue friction and heating of the parts.

20 To this end the invention consists in the features and combinations hereinafter described and claimed.

Referring to the drawings, Figure 1 is a 25 sectional view of a spindle embodying the invention. Fig. 2 is a similar view of a modified form of spindle, and Fig. 3 is a detail of the bolster.

Referring to Figs. 1 and 3, the rail A has secured thereto in the usual way the bolster-case B, in which the spindle is mounted. A 30 step-block C is secured in the bolster-case and supports the lower end of the spindle. A bearing 1 for the lower end of the spindle 2 is formed in the block C and is provided 35 with a conical lower end 3. The lower end of the spindle has a loose running fit in the bearing 1 and is provided with a conical point 5, which rests in the recess 3, thereby centering the lower end of the spindle, while allowing 40 the upper end to gyrate. The whirl 6 is formed on a sleeve 7, secured to the spindle, and the bolster-case extends up within the sleeve above the whirl, as is usual in sleeve-whirl spindles. A bolster 9 is loosely mounted 45 in the upper end of the bolster-case and is suspended from the upper end of said case by one or more lugs 10, which rest in recesses in the upper end of said tube and serve to

prevent rotation of the bolster, as well as to support said bolster freely in the end of the 50 tube.

In Fig. 2 is shown a modified form of fixed step for the spindle. In this construction the lower end of the spindle rests upon a flat surface 11, forming the bottom of a recess in a 55 step-block 12, secured in the bolster-case. The recess in the block 12 is somewhat larger than the end of the spindle, so that said spindle may move laterally in said recess in centering itself under an unbalanced load. The 60 end of the spindle is preferably flattened or rounded, so that it will travel freely over the surface 11. With this construction and arrangement—that is, with the spindle supported in the bolster-case by means of a fixed 65 step and a loose bolster suspended in said case—the spindle may be run at a high rate of speed without liability to get out of order or to unduly heat or wear the parts, and should any part become injured or worn it may be 70 readily and cheaply replaced.

What I claim as my invention, and desire to secure by Letters Patent, is—

1. The combination of a spindle, a sleeved whirl secured thereto, a bolster-case extending up within said sleeved whirl, a fixed step in said bolster-case, and a loose bolster suspended in the bolster-case and located above the whirl, substantially as described. 75

2. The combination of a spindle, a sleeved whirl secured thereto, a bolster-case extending up within said sleeved whirl, a fixed step in said bolster-case, one or more recesses in the upper end of said bolster-case, and a loose bolster located above the whirl and provided 85 with one or more lugs for engaging said recess or recesses and supporting said bolster, substantially as described. 80

3. The combination of a spindle, a sleeved whirl secured thereto, a bolster-case extending up within said sleeved whirl, a fixed step in said bolster constructed to center the lower end of the spindle, and a loose bolster mounted in said bolster-case and located above said whirl, substantially as described. 90

4. The combination of a spindle, a sleeved 95

whirl secured thereto, a bolster-case extending up within said sleeved whirl, a fixed step in said bolster constructed to center the lower end of the spindle, one or more recesses in 5 the upper end of the bolster-case, and a loose bolster located above said whirl and provided with one or more lugs for engaging said recess or recesses and supporting said bolster, substantially as described.

THOMAS GORMAN.
